Term of patent 14 years

(Cl. D52—7)

Fig. 5.Fig. 6.Fig. 7.Fig. 8.Fig. 9.FIG. 1 is a perspective view of an instrument casing, showing my new design;

FIG. 2 is a rear elevational view of the instrument casing shown in FIG. 1;

FIG. 3 is a top view of the instrument casing shown in FIG. 1;

FIG. 4 is a side elevational view of the instrument casing shown in FIG. 1;

FIG. 5 is a front perspective view of another embodiment thereof.

FIG. 6 is a front elevational view of the instrument casing shown in FIG. 5;

FIG. 7 is a rear elevational view of the instrument casing shown in FIG. 5;

FIG. 8 is a side elevational view of the instrument casing shown in FIG. 5; and

FIG. 9 is a top plan view of the instrument casing shown in FIG. 5.

The essential features of the design reside in the portions shown in full lines.

The fragmentary broken line portion of a side automobile window shown in FIG. 1 is for illustrative purposes only.

I claim:

The ornamental design for an instrument casing, substantially as shown and described.
